UNITED STATES PATENT OFFICE

171,874

SLIDE AND FILM STRIP PROJECTOR

Leo L. Zeveloff, New York, N. Y., assignor to Automatic Projection Corp., New York, N. Y., a corporation of New York

Application May 20, 1953, Serial No. 25,129

Term of patent 14 years

(Cl. D61—1)

To all whom it may concern:

Be it known that I, Leo L. Zeveloff, a citizen of the United States and a resident of the city, county, and State of New York, have invented a new, original, and ornamental Design for a Slide and Film Strip Projector, of which the following is a specification, reference being had to the accompanying drawing, forming part hereof and in which:

Fig. 1 is a front perspective view of a slide and film strip projector showing my new design.

Fig. 2 is a side elevational view.

Fig. 3 is a front elevational view.

I claim:

The ornamental design for a slide and film strip projector, substantially as shown.

LEO L. ZEVELOFF.
